UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 32,469, dated April 10, 1900.

Application filed January 8, 1900. Serial No. 787. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawing, forming a part hereof.

In the said drawing the figure is a plan view of a plate with my design placed thereon.

The outer circle X of the design is composed of two alternated ornaments A and B. A consists of a central cluster of flowers and leaves A' of different varieties, bordered by scrolls A², linked together at the bottom and parted at the top sufficient to allow the upper tulip-like flower to protrude between. The scrolls A² are supplemented by C-shaped scrolls A³, intertwined therewith and having leafed ornaments a and a' proceeding therefrom at top and bottom, respectively. B consists of a spiral ornament B', from the center of which project upwardly leaves B², having flowers B³ at their upper part.

The inner circle Y is composed of a con-

tinuous arabesque chain or border C of alternated curved and rectangular ornaments C' and C², respectively, from which extend leaves C³ and leaf-bearing stems C⁴. These ornaments are changed in form and enlarged at intervals to form the pieces C⁵, which consist of the curved ornament C⁶ and rectangular ornament C⁷, arranged at either side of a leaf C⁸, with a crown-like figure C¹⁰ above it, while extending through and above the curved ornament C⁶ at either side, on converging lines, are the leaf-bearing stems C⁹.

The two circles are separated by a circular band D, and a like band D' extends around the outside of the outer one.

This design may be applied to articles other than plates.

What I claim is—

The design for a plate or similar article substantially as herein shown and described.

Signed in New York city, New York, this 28th day of December, 1899.

CHARLES J. AHRENFELDT.
